UNITED STATES PATENT OFFICE

ELIEL SAARINEN, OF BLOOMFIELD HILLS, MICHIGAN, AND ROBERT R. KINTZ, OF MERIDEN, CONNECTICUT, ASSIGNEES TO INTERNATIONAL SILVER COMPANY, OF MERIDEN, CONNECTICUT, A CORPORATION OF NEW JERSEY

DESIGN FOR A TABLE KNIFE

Application filed February 21, 1931. Serial No. 38,788. Term of patent 14 years.

To all whom it may concern:

Be it known that we, ELIEL SAARINEN, a citizen of Finland, residing at Bloomfield Hills, Oakland County, State of Michigan, and ROBERT R. KINTZ, a citizen of the United States, residing at Meriden, county of New Haven, State of Connecticut, have invented a new, original, and ornamental Design for a Table Knife, of which the following is a specification, reference being had to the accompanying drawings, forming a part thereof:

Fig. 1 is a plan view of a table knife showing our new design; and

Fig. 2 is a side view of the same.

The essential feature of the design consists in the general proportions and outline of the knife which comprises a relatively long handle and short blade having substantially the configuration shown.

We claim:

The ornamental design for a table knife substantially as shown and described.

ELIEL SAARINEN.
ROBERT R. KINTZ.
